(57) **CLAIM**

The ornamental design for a grille for an automobile, as shown and described.

DESCRIPTION

FIG. 1 is a right-front, perspective view of the grill for an automobile of my new design;

FIG. 2 is a front view thereof;

FIG. 3 is a top view thereof;

FIG. 4 is a bottom view thereof; and,

FIG. 5 is a left-side view of the design of FIG. 1, the right-side view being a mirror image thereof.

The rear view of my invention forms no part of the claimed invention.
